(57) **CLAIM**

The ornamental design for a shoe luggage case, as shown and described.

DESCRIPTION

FIG. 1 is a front elevational view of a shoe luggage case embodying my new design;

FIG. 2 is a left side elevational view thereof;

FIG. 3 is a right side elevational view thereof;

FIG. 4 is a rear elevational view thereof;

FIG. 5 is a top view thereof;

FIG. 6 is a bottom view thereof;

FIG. 7 is a top view thereof in an open configuration; and,

FIG. 8 is a front view thereof.

The broken lines shown in the drawings illustrate the environment of the article and form no part of the claimed design.
